UNITED STATES PATENT OFFICE.

ROBERT HUGH COLLINGHAM, OF RUGBY, ENGLAND, ASSIGNOR TO GENERAL ELECTRIC COMPANY, A CORPORATION OF NEW YORK.

VAPOR GENERATOR.

Application filed June 30, 1925, Serial No. 40,674, and in Great Britain July 2, 1924.

This invention relates to improvements in vapor generators, and more particularly to the type of generator in which mercury is evaporated in revolving tubes.

5 The object of the invention is to provide a sealing device for such revolving tubes to prevent the leakage of mercury vapor. It is desirable in this type of generator to provide sealing devices in which the frictional 10 losses between the stationary and rotating parts of the seals are reduced to as low value as possible, and to attain this, the present invention comprises providing each 15 end of the rotating tube with a number of impellers rotating in separate compartments which create a pressure, which pressure counterbalances the static head of the fluid mercury which forms the operating fluid of the sealing devices.

20 The invention further comprises details of construction hereinafter described.

The accompanying drawing, Fig. 1, illustrates one method of carrying this invention into effect, and illustrates a single tube of a 25 boiler of the type above described, the ends of the tube being shown in section, and Fig. 2 is a detail sectional view on a large scale of certain parts shown in Fig. 1.

In the drawing, 1 represents a tube which 30 is adapted to be supplied with mercury, and to be rotated by any suitable means at a suitable speed. This tube is provided with end connections 2 and 3, which communicate with the interior of the tube and rotate with 35 it, the fluid mercury being led in through the connection 2, and the vapor generated being led away through the rotating connection 3. The tube is supported on ball or roller bearings 4, which are suitably supported from the generator casing. 40 5—5 are casings for the sealing device arranged at each end of the tube 1, and contain diaphragms 6 which divide the interior of the casings into compartments in which rotate members 7 secured to the rotating connections 2 and 3. These members 7 are provided with vanes on one side. On the rotating connections 2 and 3 are secured collars 8 which are engaged by carbon rings 9 carried 45 by flexible metallic bellows 10, which are supported from the casing 5. The elasticity of the metal bellows provide the necessary force to hold the carbon rings 9 in contact with the rotating collars 8.

55 Mounted on the rotating connection 3

through which the vapor is led from the rotating tube 1, and inside the casing 5, is provided an impeller 11 having vanes so arranged that the pressure built up during rotation is in opposition to the pressure built up by the impellers on the member 7. Between the impellers a diaphragm 12 is provided. The casings are also provided with end covers 13 and 14, cover 14 being fitted with a pipe 15 which leads the mercury vapor generated in the tube to a turbine or other suitable device in which it can be utilized. The other cover 13 is provided with a pipe 16 through which fluid mercury is fed into the rotating tube from the sump 70 of a vapor condenser 17, it being understood that this may be the condenser for a turbine to which the boiler supplies operating vapor. Pipes 18 and 19 communicate with the interior of the casings 5 of the sealing devices, and are provided with mercury traps 20 and 21 fitted with baffles 22. Traps 20 and 21 are provided with drain connections 20^a and 21^a, through which the mercury which accumulates in the traps may be, from time to time, drawn off. Drain connections 20^a and 21^a may lead to any suitable point.

When running under normal conditions, the difference in level of the mercury indicated at 23 is equal to the vacuum in inches 85 of the mercury held in the condenser. A pipe 24 feeds mercury from the sump of the condenser 17 to the space 25 between the walls of the diaphragm 12 and from this into the compartments in which the impellers 7 90 and 11 are rotating.

In operation, when the tube 1 is rotating at a suitable speed, the impellers 7 build up a pressure in the compartments 5 in which they rotate, the total of which pressure balances the static head of the fluid mercury fed by the pipes 16 and 24 to the sealing devices. As a result, a mercury seal will be established, little if any mercury finding its way through the seals to pipes 18 and 19 100 where they connect to casings 5. The impeller 11 is especially provided at the seal situated at the end of the rotating tube 1, from which vapor is led by the pipe 15, in order to prevent the possibility of the flow 105 of any liquid mercury through the pipe 15, along with the mercury vapor. The summation of the pressure of the mercury vapor and the pressure due to the impeller 11, balances the static head of the condensed mer- 110

cury vapor between the level in the sump of the condenser 17, and the center line of the rotating tube 1, in which the mercury is evaporated.

5 The function of the carbon rings bearing on the rotating collars 8 is to prevent any shaft leakage of mercury vapor from the sealing devices to the atmosphere. The vacuum in the condenser does not operate on the carbon ring seals through the pipes 18 and 19, as the difference in level 23 of the mercury in the traps 20 and 21 and the U-shaped sealing pipe, is sufficient to prevent this. The pressure difference across the carbon rings 8, 9 is negligible and the power expended in overcoming friction between the carbon rings and the rotating collars is due entirely to the extension of the metallic bellows. The wear, therefore, 10 on the carbon rings at the speeds usually employed on such boilers is very small, and gives a long life to the carbon rings.

If, for any reason, the tube 1 should cease to rotate, then owing to the spacing of the impellers the mercury standing in the pipes 16 and 24 and in the sump of the condenser would be discharged through the centrifugal sealing devices into the mercury traps 20 and 21. The vapor also under pressure in the tube 1 would discharge back through the centrifugal sealing devices and would exert its pressure to hold the carbon rings tightly against the collars, at the same time forcing its way through the mercury contained in the traps 20 and 21, and returning by means of the pipes 18 and 19 back to the condenser, where the vapor would be condensed. There will, therefore, be no appreciable leakage of mercury due to the tubes being stopped from any unforeseen cause.

Although I have described and illustrated one particular form of my invention, I do not wish to limit myself to this particular design, as in place of a single carbon sealing ring at each end of the tube, I might provide a plurality of rings, and a plurality of metallic bellows at each end of the tube.

Also, although I have shown only one tube of the boiler, it will be understood that a complete boiler may comprise any suitable number of tubes.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. The combination with a vapor generator comprising a support and a tube ro-

tatably mounted therein, of sealing means for an end of the tube comprising a casing, impeller means carried by the tube inside the casing, a liquid chamber located above the tube, said chamber being adapted to contain a supply of liquid, and conduits connecting the chamber at points above and below the level of the liquid in the chamber to the casing at opposite sides of said impeller means, the conduit connecting the casing with the chamber below the level of the liquid being in communication with the interior of the tube.

2. The combination with a vapor generator comprising a support, a tube rotatably mounted therein, a condenser chamber located above the tube and adapted to contain a supply of liquid, a conduit connecting the chamber to the tube through which liquid is supplied to the tube, and a conduit connected to the tube for conveying vapor therefrom, of sealing means for an end of the tube comprising a casing, impeller means carried by the tube inside the casing, a conduit connecting the condenser chamber below the liquid level therein with the casing to set up a static head in the latter, said impeller means being adapted to build up pressure in opposition to the static head in said condenser chamber, and a pipe connecting the lower pressure side of said impeller to the condenser chamber above the level of the liquid therein.

3. The combination with a vapor generator comprising a support, a tube rotatably mounted therein, a condenser chamber located above the tube and adapted to contain a supply of liquid, a conduit connecting the chamber to the tube through which liquid is supplied to the tube, and a conduit connected to the tube for conveying vapor therefrom, of sealing means for an end of the tube comprising a casing, impeller means carried by the tube inside the casing, a conduit connecting the condenser chamber below the liquid level therein with the casing to set up a static liquid head in the latter, said impeller being adapted to building up a pressure in opposition to the static head in said supply chamber, a pipe connecting the lower pressure side of said impeller to the condenser chamber above the level of the liquid therein, and a sealing ring for the tube located between the casing and the tube.

4. The combination with a vapor generator comprising a support, a tube rotatably mounted therein and a conduit through which vapor generated in the tube is withdrawn, of a sealing means for the tube comprising a casing, two spaced impeller means carried by the tube inside the casing, a liquid chamber located above the tube, said chamber being adapted to contain a supply of liquid, a pipe connecting the lower end of the liquid chamber to the space between said im-

1 peller means, the casing being adapted to provide a space adjacent the outer end of one of said impeller means which is in communication with the first-named conduit, and a space 5 adjacent the outer end of the other impeller means, and conduit means connecting the last-named space with the liquid chamber above the liquid level.

5. In a vapor generator of the rotating tube type, the combination of a support, a tube having open ends rotatably mounted therein, casings surrounding the ends of the tube whereby said casings are in communication with and connected by said tube, a conduit 10 for supplying liquid to each of said casings, a conduit for conveying vapor from one of said casings, a liquid chamber with which the supply conduits connect, said chamber being adapted to set up through said connections a static pressure in the casings, a packing means for the tube end in each casing comprising a yieldingly pressed sealing ring supported from the casing and a collar carried by the tube against which the ring packs, 15 and impeller means mounted on the tube ends in said casings for building up pressures to counterbalance the static pressure of the liquid from said chamber.

6. The combination with a vapor generator comprising a vaporizing tube and a supporting means in which said tube is rotatably mounted, of means for conducting a liquid to be vaporized through said tube, comprising tubular open end members forming axial extensions of the tube, casings carried by the supporting means into which said members project, means including a conduit connected with each casing for supplying liquid thereto under pressure, one of said 20 conduits terminating adjacent the open end of one of the tubular members whereby it is

in communication therewith, an outlet conduit for vaporized liquid connected with the casing surrounding the other tubular member and being in communication with the 45 open end thereof, and a sealing means for the tube comprising impeller means carried by the tubular members in each casing which operate to create pressure in opposition to the liquid pressure therein, and a second impeller means located in the casing with which the outlet conduit is connected, said impeller means being located between the outlet conduit connection with said casing and the supply conduit connection with said casing. 50 55

7. The combination with a vapor generator comprising a vaporizing tube adapted to provide a conduit for a liquid to be vaporized, and a supporting means in which said tube is mounted to rotate about its longitudinal axis, of a pair of tubular end connections for the tube, said end connections having open outer ends and being connected with the tube to rotate coaxially therewith, and sealing means for the end connections comprising casings into which said end connections project, a packing device in each casing surrounding the end connection therein and forming a closure for one end of each casing, an end cover forming a closure for 60 the opposite end of each casing, a rotary liquid sealing device in each casing between the end cover and the packing device having impellers which rotate with the end connections to balance a static liquid pressure in 65 each casing and means connected with each casing for supplying a liquid thereto under static pressure. 70 75

In witness whereof, I have hereunto set my hand this 10th day of June 1925.

ROBERT HUGH COLLINGHAM.
